UNITED STATES PATENT OFFICE.

JOHN F. ABEL, OF BURLINGTON, IOWA.

ATTACHMENT FOR CARBURETORS.

Application filed March 19, 1924. Serial No. 700,301.

- This invention relates to an attachment for carburetors and is an improvement on my Patent Number 1,269,146, dated June 11, 1918, the object being to provide a carburetor with means for delivering water, glycerine and air to the same for increasing the efficiency of the explosive charge produced thereby, whereby greater power will be obtained from the mixture.
- Another and further object of the invention is to provide an attachment for a carburetor which is provided with a sight feed indicator having a valve for controlling the supply of water and glycerine to the explosive charge produced by the carburetor whereby the amount of glycerine and water admitted to the explosive charge can be regulated from the dash of the motor vehicle to which the device is attached.
- A still further object of the invention is to provide means for admitting a small proportion of the exhaust gases of the internal combustion engine to which the attachment is applied, to the explosive charge into which is introduced a small amount of air from the atmosphere to supply the necessary oxygen.
- Other and further objects and advantages of the invention will be hereinafter set forth and the novel features thereof defined by the appended claims.
- In the drawings,
- Figure 1 is a vertical section through a portion of a motor vehicle showing an internal combustion engine in elevation with my improved carburetor attachment applied;
- Figure 2 is a detail section on line 2—2 of Figure 1;
- Figure 3 is a vertical section through the sight feed indicator and control; and
- Figure 4 is a detail inverted section of the nipple for connecting the pipe to the water jacket.
- In the drawing 1 indicates a body of a motor vehicle provided with an instrument board 2. Arranged within the body is an internal combustion engine 3 which is provided with an exhaust manifold 4, intake manifold 5 and carburetor 6 which may be of any of the well known forms of carburetors now in use, the above description being given so that the application of my attachment can be readily understood.
- In the embodiment of the invention as herein shown, I secure a Y coupling 7 in the wall of the mixing chamber of the carburetor below the throttle valve 8, the branches
- 9 and 10 of which are provided with apertures 11 and 12 for admitting air into the fluid passing therethrough as will be herein-after fully described. While I have shown the Y coupling 7 installed in the mixing chamber below the throttle valve, I do not wish to limit myself to placing this coupling at this exact point, as I am aware that it can be disposed in the intake manifold or in the carburetor above the throttle valve without departing from the spirit of my invention.
- Secured to the instrument board 2 is a sight feed indicator 13 provided with an inlet 14 and an outlet 15 to which are connected nipples 16 and 17. The sight feed indicator is provided with a plug 18 at its upper end forming a valve casing which is provided with a removable valve seat 19 in the form of a tube which extends down into a glass tube 20 of the indicator so that the passage of fluid through the tube 19 will be visible from the driver's seat of the motor vehicle.
- Mounted within the plug 18 is a threaded valve stem 21 which is provided with a needle valve 22 at its lower end adapted to cooperate with the seat 19 for regulating the passage of fluid through the indicator or for completely cutting off the passage of fluid therethrough, the valve being provided with a wheel 23 at its upper end for manipulating the same.
- Secured in the nipple 16 of the indicator by coupling 24 is one end of a copper pipe 25, the other end of which is secured to a nipple 26 by a coupling 27, said nipple 26 being tapped into the water jacket of the internal combustion engine and is provided with a screen 35 for preventing foreign particles in the water from being drawn through the same.
- The nipple 17 is provided with a coupling 28 in which is secured one end of a copper pipe 29, the other end of which is secured to the branch 9 of the Y 7 by a coupling 30. By this construction the water in the water circulating system of the motor vehicle is drawn by the suction induced in the charge forming device through the sight feed indicator and delivered into the explosive charge, air being admitted at 11 so as to aerate the water and supply additional oxygen to the explosive charge.
- Secured to the branch 9 of the Y 7 by a coupling 31 is a copper pipe 32, the other

end of which is secured to a nipple 34, which is tapped into the exhaust manifold 4, preferably back of the second cylinder of the internal combustion engine.

5 The exhaust gases are drawn by the suction of the engine cylinder through the pipe 32 and air is admitted at the aperture 12 in the branch 10 of the Y 7 so as to reduce the temperature of these exhaust gases to a certain extent and to supply additional oxygen.

10 It will be noted that the Y 7 which is tapped into the carburetor is so connected to the water circulating system and the exhaust gas manifold that the exhaust gases and water are first supplied with air from the atmosphere and then this exhaust gas and water are mixed and delivered into the explosive charge so as to increase the moisture of the explosive charge, whereby the 15 formation of carbon in the cylinders of the internal combustion engines will be reduced to a minimum.

15 In order to supply an alcohol to the water which is delivered to the explosive charge, I place within the radiator or cooling system of the internal combustion engine an alcohol, such as glycerine or the like, which becomes thoroughly mingled with the water and is delivered with the water being drawn 20 into the explosive charge by the suction of the engine into the cylinders of the engine with the explosive charge so as to moisten and supply glycerine to prevent the formation 25 of carbon and to increase the efficiency 30 of the explosive charge.

35 As the amount of glycerine and water delivered to the explosive charge is small in comparison with the capacity of the cooling system of the internal combustion engine, 40 the amount drawn from the cooling system does not in any way affect the efficiency of the cooling system of the internal combustion engine and I am able to produce an explosive charge for an internal combustion 45 engine which will increase the mileage and produce a charge which has many advantages over the ordinary explosive charge now produced by a carburetor.

50 From the foregoing description it will be seen that I have provided a carburetor attachment in which water and glycerine are drawn into the explosive charge mixed with air and at the same time a portion of the products of combustion which are cooled by the admission of air from the atmosphere is delivered with the glycerine and water into the explosive charge at such a point that it thoroughly mingle with the explosive charge and produces an explosive 55 charge of high efficiency.

60 What I claim is:—

1. The combination with an internal combustion engine having a water cooling system containing water and glycerine, an ex-

haust manifold, intake manifold and a 65 charge forming device connected thereto, of a Y coupling arranged to enter the carbureting passage of the charge forming device, each branch of the Y being provided with an air inlet, means for supplying glycerine mixed with water from the cooling system of said internal combustion engine to one branch of the Y coupling, and means for supplying exhaust gases to the other branch of said Y coupling from the exhaust 70 manifold of said internal combustion engine.

2. The combination with an internal combustion engine having a water cooling system, exhaust manifold, intake manifold and charge forming device connected thereto, of 80 a Y coupling in communication with the charge forming device, means for supplying glycerine mixed with water to said Y coupling from said water cooling system, means for supplying exhaust gases to said Y coupling, said Y coupling being provided with air inlets for supplying air to the fluid passing through said coupling and means for indicating the flow of water and glycerine to 85 said coupling from said water cooling system. 90

3. The combination with an internal combustion engine having a water cooling system, exhaust manifold, intake manifold and charge forming device connected thereto, 95 said water cooling system being adapted to contain water and glycerine, of a Y coupling arranged in the charge forming device, each branch of the Y coupling being provided with an opening for admitting air thereto, means for supplying glycerine mixed with water from said cooling system to one branch of said Y coupling, means for supplying exhaust gases to the other branch of said Y coupling, means for indicating the flow of water and glycerine from said cooling 100 system to said coupling and means for controlling the supply of water and glycerine to said coupling. 105

4. The combination with an internal combustion engine of a carburetor for producing an explosive charge for said engine, a coupling in communication with the mixing chamber of said carburetor provided with air inlets, means for delivering to said coupling a mixture of water and glycerine, means for delivering to said coupling exhaust gases produced by said engine, said exhaust gases and mixture of water and glycerine being mixed with air through the 115 air inlets of said coupling before they are delivered to the mixing chamber of said coupling and means for controlling the volume of water and glycerine delivered to said coupling. 120

125 In testimony whereof I hereunto affix my signature.

JOHN F. ABEL.
